United States Patent Office

Des. 208,122
Patented July 18, 1967

208,122

SIGNAL LIGHT

David H. Trott, 3351 Stettinius,
Cincinnati, Ohio 45208

Filed Oct. 24, 1966, Ser. No. 4,397

Term of patent 14 years

(Cl. D72—1)

FIG. 1

FIG. 4

FIG. 2

FIG. 5

FIG. 3

FIG. 1 is a top plan view of a signal light showing my invention,

FIG. 2 is a side elevational view thereof,

FIG. 3 is a bottom plan view thereof,

FIG. 4 is a rear elevational view thereof, and

FIG. 5 is a front elevational view thereof.

I claim:

The ornamental design for a signal light, substantially as shown.
